(57) **CLAIM**

The ornamental design for a smart watch, as shown and described.

DESCRIPTION

FIG. 1 is a bottom, front, and right perspective view of a smart watch showing our new design.

FIG. 2 is a bottom, rear, and left perspective view of the smart watch of FIG. 1.

FIG. 3 is a bottom plan view of the smart watch of FIG. 1.

FIG. 4 is a top plan view of the smart watch of FIG. 1.

FIG. 5 is a left side elevational view of the smart watch of FIG. 1.

FIG. 6 is a right side elevational view of the smart watch of FIG. 1.

FIG. 7 is a front elevational view of the smart watch of FIG. 1; and,

FIG. 8 is a rear elevational view of the smart watch of FIG. 1.

The broken lines shown in the drawings depict portions of the smart watch and form no part of the claimed design.

1 Claim, 7 Drawing Sheets
